(57) **CLAIM**

The ornamental design for a tire cleaning brush, as shown and described.

DESCRIPTION

FIG. 1 is a perspective view of our new design for a tire cleaning brush, the handle being illustrated in broken lines for environmental purposes only and forming no part of the claimed design;

FIG. 2 is a side elevational view thereof, the opposite side being a mirror image thereof;

FIG. 3 is a top plan view thereof;

FIG. 4 is a bottom plan view thereof;

FIG. 5 is a front elevational view thereof; and,

FIG. 6 is a rear elevational view thereof.
